UNITED STATES PATENT OFFICE.

SAMUEL MUNDHEIM, OF BROOKLYN, NEW YORK.

DESIGN FOR A HAT.

No. 38,081.

Specification for Design.

Patented May 22, 1906.

Application filed March 9, 1906. Serial No. 305,181. Term of patent 3½ years.

To all whom it may concern:

Be it known that I, SAMUEL MUNDHEIM, a citizen of the United States, residing at Brooklyn, in the county of Kings and State of New York, have invented a new, original, and ornamental Design for a Hat, of which the following is a specification, reference being had to the accompanying drawings, forming a part thereof, and in which—

Figure 1 is a plan, and Fig. 2 a side perspective view, of a hat bearing and incorporating my design.

I claim—

The ornamental design for a hat, as shown.
SAMUEL MUNDHEIM.
